(57) **CLAIM**

The ornamental design for a Hawaiian island-shaped set of serving trays, as shown and described.

DESCRIPTION

FIG. 1 is a perspective view of a Hawaiian island-shaped set of serving trays, showing the new design;

FIG. 2 is a front elevational view of a first tray thereof;

FIG. 3 is a rear elevational view thereof;

FIG. 4 is a right-side elevational view thereof;

FIG. 5 is a right-side elevational view thereof;

FIG. 6 is a top plan view thereof;

FIG. 7 is a bottom plan view thereof;

FIG. 8 is a front elevational view of a second tray thereof;

FIG. 9 is a rear elevational view thereof;

FIG. 10 is a right-side elevational view thereof;

FIG. 11 is a right-side elevational view thereof;

FIG. 12 is a top plan view thereof;

FIG. 13 is a bottom plan view thereof;

FIG. 14 is a front elevational view of a third tray thereof;

FIG. 15 is a rear elevational view thereof;

FIG. 16 is a right-side elevational view thereof;

FIG. 17 is a right-side elevational view thereof;

FIG. 18 is a top plan view thereof;

FIG. 19 is a bottom plan view thereof;

FIG. 20 is a front elevational view of a fourth tray thereof;

FIG. 21 is a rear elevational view thereof;

FIG. 22 is a right-side elevational view thereof;

FIG. 23 is a right-side elevational view thereof;

FIG. 24 is a top plan view thereof;

FIG. 25 is a bottom plan view thereof;

FIG. 26 is a front elevational view of a fifth tray thereof;

FIG. 27 is a rear elevational view thereof;

FIG. 28 is a right-side elevational view thereof;

FIG. 29 is a right-side elevational view thereof;

FIG. 30 is a top plan view thereof; and,

FIG. 31 is a bottom plan view thereof.

The broken lines showing a wall in FIG. 1 are included for the purpose of illustrating the invention in use alternately as a wall display, and form no part of the claimed design.
